UNITED STATES PATENT OFFICE.

MICHAEL MAIELLO, OF WASHINGTON, PENNSYLVANIA.

CLEANSING APPARATUS.

1,172,150.

Specification of Letters Patent. Patented Feb. 15, 1916.

Application filed July 8, 1915. Serial No. 38,678.

To all whom it may concern:

Be it known that I, MICHAEL MAIELLO, a citizen of the United States, residing at Washington, in the county of Washington 5 and State of Pennsylvania, have invented certain new and useful Improvements in Cleansing Apparatus; and I do declare the following to be a full, clear, and exact description of the invention, such as will enable others skilled in the art to which it 10 pertains to make and use the same.

This invention relates to improvements in apparatus for cleaning and more particularly to apparatus of this character for 15 cleaning clothing.

The object of the invention is to provide a simply constructed and efficient cleaning apparatus which will remove grease and paint spots from clothing and the like.

20 Another object is to provide an apparatus of this character so constructed that the cleaning operation may be quickly and cheaply accomplished.

With these and other objects in view, the 25 invention consists of certain novel features of construction and the combination and arrangement of parts as will be hereinafter more fully described and claimed.

In the accompanying drawings: Figure 1 30 represents a side elevation of an apparatus constructed in accordance with this invention with the casing thereof in section for convenience in illustration; and showing a stand for supporting it; Fig. 2 is a trans- 35 verse section taken on line 2—2 of Fig. 1; Fig. 3 is a similar view taken on line 3—3 of Fig. 1; Fig. 4 is an enlarged horizontal section taken on line 4—4 of Fig. 1; Fig. 5 is an enlarged detail section through one of 40 the cups showing its sponge arranged in operative relation thereto.

In the embodiment illustrated a supporting base is shown in the form of a board 1 having a casing 2 fixed thereto and within 45 which the apparatus constituting this invention is inclosed. The base board 1 has an opening therein through which a cleaning brush 3 projects and which will be herein- 50 after more fully described in detail. Two cylindrical tanks 4 and 5 are mounted in the casing 2 one above the other, the tank 5 being designed to contain a drying fluid such as turpentine and is smaller than the tank 4 which is designed to contain any suitable 55 cleansing fluid. The tank 5 is mounted to

revolve relatively to the tank 4, a chain 6 being shown connecting them. The smaller tank 5 is shown mounted on suitable standards 7 and 8 while the tank 4 is supported on a shaft 9 mounted in suitable bearings 10 60 at opposite ends of the casing.

A motor 11 is mounted within the casing 2 preferably at the upper right hand portion thereof and the shaft 12 of this motor is provided at its inner end with a pinion 13 65 which meshes with a gear wheel 14 revolvably mounted on a shaft 15. This gear wheel 14 meshes with another gear wheel 16 which is fixed to the shaft 9 of the tank 4 so that the turning of said gear wheel 16 70 rotates the tank, the teeth of the meshing gears being proportioned so that the gear 16 will rotate about fifteen times every minute more or less. Another gear 17 meshes with the gear 14 and has fixed to its inner face a 75 beveled gear 18 which meshes with a correspondingly beveled pinion 19 carried by a shaft 20 with which the brush 3 is connected by means of a tubular standard 21 having a receptacle 22 at its upper end provided with 80 a perforated diaphragm 23 and to which the shaft 20 is fixed so that on the rotation of the shaft 20 the receptacle and standard 21 will also be rotated thereby rotating with them the brush 3. Arranged above the 85 brush 3 and communicating with the tubular standard 21 is a reservoir or receptacle 24 which receives the fluid from the perforated diaphragm 23 and distributes it through the bristles of the brush 3, the latter 90 being rapidly rotated and engaged with the article to be cleaned. This operation quickly and rapidly removes any grease or other spots from said article by the engagement of the bristles of the brush therewith. 95

Tubes 26 and 27 have their lower ends arranged to discharge into the receptacle 22 above the perforated diaphragm 23 thereof. These tubes are provided at their upper ends with cup-shaped or flared mouths 27' 100 which are disposed in the path of outlet tubes 28 and 29 carried by the ends of the tanks 4 and 5, the outer ends of said tubes 28 and 29 being provided with feeding devices in the form of sponges 28' and 29' 105 respectively through which the fluid from the tanks is conveyed to the cup-shaped mouths 27' of the supply tubes 26 and 27 and on each rotation of the tanks a single drop of fluid is discharged through the sponges on 110

the ends of the tubes 28 and 29 into said cups 27 and passes down onto and through the perforated diaphragm 23 and is conducted through the tubular standard 21 to 5 the distributing chamber 24 of the brush 3 and passes from said chamber onto the bristles of said brush by means of which it is applied to the article to be cleansed.

A standard 30 is shown rising from the 10 base plate 1 at one end of the casing and is designed to assist in supporting the shafts on which the gear wheels are mounted.

A push button 31 is here shown located in a handle 32 on the top of the casing 2 and 15 is connected with the motor 11 by suitable wiring 33 so that when said button is actuated the motor will be cut off and the operation of the machine stopped in a manner well understood.

20 Each of the tanks 4 and 5 is provided with a suitable filling aperture 34 provided with the usual screw cap closure 35.

From the above description it will be obvious that when the motor 11 is in operation 25 the train of gears connected with the shaft thereof will be operated, thereby slowly turning the tanks 4 and 5 which contain the cleansing fluid thus causing the sponges mounted in the outlet pipes thereof to engage the cup-shaped mouths of the supply tubes 26 and 27 and thus feed the cleansing fluid to the brush 3 at the same time rapidly rotating said brush to effect the cleaning operation.

30 In Fig. 1 a rest or stand 36 is shown on which the cleaner is designed to be placed when not in use so that the brush 24 which projects below the base 1 will not be injured. This stand as shown conforms in shape and 35 size to the base 1, although not necessarily so, and comprises a body portion 37 which may be either solid or hollow but preferably solid to sustain the weight of the apparatus to be supported thereby. The upper face 40 of this stand is preferably covered with cloth 39 or other suitable fabric to produce a snug fit between the members and prevent the said apparatus from slipping off. An upstanding lip or flange 40 is shown at the 45 rear of said stand to assist in retaining the apparatus thereon. The upper face of the stand 36 has a recess 41 formed therein opposite the opening in the base 1 through 50 which the brush projects so that when said stand is placed under the apparatus to be supported this recess will receive the brush and prevent injury to the bristles.

Copies of this patent may be obtained for five cents each, by addressing the "Commissioner of Patents, Washington, D. C."

I claim as my invention:

1. A device of the character described comprising a base, a cleaning fluid containing tank revolubly mounted on said base, a brush revolubly mounted on said base, a tube extending from said brush, means for feeding the fluid contained in said tank into said tube at predetermined intervals, and means for revolving said tank and said brush, as and for the purpose set forth. 60

2. A device of the character described comprising a base having an opening therein, a cleaning fluid containing tank revolubly mounted on said base, a brush extending through the opening in said base, a liquid feeding device eccentrically carried by said tank, a tube extending from said brush, means for revolving said tank for 70 engaging said feeding device with the free end of said tube at predetermined intervals, and means for revolving said brush, as and for the purpose set forth. 75

3. A device of the character described comprising a base having an opening therein, a fluid containing tank revolubly mounted on said base, a fountain brush extending through said opening, a tube extending from one end of said tank, an absorbent feeding device carried by the outer end of said tube, a tube extending from said brush and provided at its free end with a flared mouth, said mouth being disposed in the path of said feeding device for feeding 80 the fluid contained in said tank to said tube at predetermined intervals. 85

4. A device of the character described comprising a base having an opening therein, fluid containing tanks horizontally arranged one above the other, means under the control of the operator for rotating one of said tanks, means connecting said positively rotated tank with the other tank and adapted to impart rotary movement thereto, 95 outlets for said tanks having absorbent feeding devices to receive the fluid from said tank, a fountain brush projecting through the opening in said base, and means arranged in the path of the feeding devices 100 of said tanks for feeding the fluid contained therein into said brush. 105

In testimony whereof I have hereunto set my hand in presence of two subscribing witnesses.

MICHAEL MAIELLO.
